(57) **CLAIM**

The ornamental design for a robotic cleaner as shown and described.

DESCRIPTION

FIG. 1 is a front top perspective view of a robotic cleaner showing our new design;

FIG. 2 is a bottom rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front top perspective view of the robotic cleaner showing the cover in an opened state; and,

FIG. 10 is a rear top perspective view of the robotic cleaner showing the cover in an opened state.

The broken lines shown in the drawings are included for the purpose of illustrating portions of the robotic cleaner that form no part of the claimed design.
